UNITED STATES PATENT OFFICE.

ANDREW MALINOVSKY, OF BELLEVILLE, ILLINOIS, ASSIGNOR TO THE MALINITE COMPANY, OF WILMINGTON, DELAWARE, A CORPORATION OF DELAWARE.

BRICK-MACHINE.

1,310,953.

Specification of Letters Patent. Patented July 22, 1919.

Application filed December 17, 1917. Serial No. 207,442.

To all whom it may concern:

Be it known that I, ANDREW MALINOVSKY, a citizen of the United States, residing at Belleville, in the county of St. Clair and State of Illinois, have invented certain new and useful Improvements in Brick-Machines, of which the following is a specification.

The invention has to do with improved means, simple and efficient, for imparting to bricks in the act of molding a characteristic surface marking such as a rough or stippled face.

In order that the invention may be readily understood a preferred embodiment of the same is set forth in the accompanying drawings and in the following detailed description based thereon. Obviously, however, the invention is susceptible of embodiment in other and varied constructional forms without departure from the essence thereof, wherefore the drawing and description are to be taken in an illustrative rather than in an unnecessarily limiting sense. In the drawings—

Figure 1 is an end elevation, fragmentary in character, showing the salient parts of the brick machine embodying the invention, the medial portion being broken away on a line 1—1 of Fig. 2, below the horizontal level illustrated in said figure;

Fig. 2 is a plan view with the central portion shown in horizontal section;

Fig. 3 is a fragmentary view in end elevation of a portion shown in Fig. 1, illustrating the parts in a different position;

Fig. 4 is a side elevation with certain parts shown in vertical section on the line 4—4 of Fig. 1; and

Fig. 5 is a similar view to Fig. 4, the section being taken on the line 5—5 of Fig. 2 and illustrating the working parts in a different position.

In the drawings is shown a typical brick machine having the usual lower battery of rams 11, 12, 13 and 14, and the coöperating upper battery of rams 15, 16, 17 and 18, arranged side by side and supplied with material from the hopper indicated at 19, the two members of each pair of rams disposed end to end and acting upon material fed therebetween, the formed brick being discharged from the mold onto the table 20.

The machine provides means for impart-

ing desired rough configuration, herein generally referred to as a stippled surface, to one end and one edge of each brick. Mechanism is provided, operated automatically and in isochronism with the operation of the rams themselves, by means of which the end and edge faces of the bricks are stippled in the act of molding the same, the stipple plates being so mounted as to be suddenly removed from contact with the formed brick by a swinging or rectilinear movement as the brick reaches a position ready to be discharged onto the table 20.

Carried by the mounting of the upper sets of rams 15, 16, 17 and 18 in suitable bearings, for upward and downward movement with the rams, are two parallel shafts 21 and 22 which are geared by means of the meshing pinions 23, 24, the shaft 21 having fixed thereon two crank arms 25 and 26, the former connected by means of an expansion spring 27 with a suitable support 28 for rocking the shaft 21 in one direction and the latter arm 26 being provided with a roller 29 adapted to be engaged by the lower end of a vertically adjustable trip bar 30 as the upper battery of rams rise, whereby to rock the shaft 21 in the opposite direction. The shaft 22 has fixed thereon bevel gears 31, 32, in mesh with bevel gears 33, 34, carried by shafts 35, 36 arranged at right angles to the shaft 22. The shafts 35, 36 have suspended therefrom respectively stipple plates 37, 38, and the shaft 22 has suspended therefrom four similar stipple plates 39, 40, 41 and 42.

The said stipple plates 37 and 38 are adapted to surface the edges of the brick formed in the outside molds of the battery while the plates 39, 40, 41 and 42 are arranged to surface the end faces of all four bricks turned out by the battery of molds. The stipple plate for surfacing the edges of the intermediate bricks of the battery of molds are differently mounted and operated as will now be described.

Between each of the intermediate rams 100 and its adjacent outside ram there is provided a space 43 on the one hand and 44 on the other, and also a central space 45. Transversely slidably mounted in the rams 16 and 17 are arranged rods 46 and 47, 48 and 49. The rods 46 and 47 of the ram 16

carry wedge blocks 50, 51 at their inner ends and the rods 48, 49 of the ram 17 carry wedge blocks 52, 53 at their inner ends, each of the rods 46, 47, 48 and 49 being 5 screw threaded at its outer end and having mounted thereon stipple plates, the rods 46 and 47 carrying the stipple plates 54 and the rods 48, 49 carrying the stipple plates 55. Extending between the adjacent faces 10 of the wedge blocks 50, 51 on the one hand and 52, 53 on the other is a wedge member 56 having an overhanging lip 57 extending beyond the shaft 22 and inclosing an eccentric 58 fixed upon said shaft 22, the rocking 15 of the shaft 22 causing the wedge member 56 to be reciprocated, thus wedging apart the wedge blocks 50—52 and 51—53, compressing the springs 59, 60, 61 and 62 which encircle the rods 46, 47, 48 and 49, and moving 20 the stipple plates 54 and 55 outwardly from the position shown in Fig. 2 to that shown in the central part of Fig. 3.

In operation the material supplied by the hopper 19 drops into the cavity 63 of 25 the plunger feed 64, resting upon the feed table at 65. The plunger 64 moves forwardly beneath the elevated battery of rams 15, 16, 17 and 18 while the stipple plates 37, 38, 39, 40, 41 and 42 are swung 30 outwardly to the position indicated in Fig. 3 in full lines as to one of said stipple plates, and as indicated in dotted lines in Fig. 4 as to other of said stipple plates, the stipple plates 54 and 55 also being in retracted position as indicated in Fig. 3. The material, carried forward in the cavity 63 by the advancing plunger 64, drops into the mold cavity resting upon the upper face of the lower battery of rams 11, 12, 13, and 14 and 35 any excess of material is removed to the table 65 by the advance portion 64^a of the plunger as said plunger recedes to the position shown in Figs. 4 and 5. As the upper battery of rams starts to descend, spring 27 40 rocks the shaft 21 and through it the shaft 22 causing the stipple plates 37, 38, 39, 40, 41 and 42 to swing to a vertical position and the stipple plates 54 and 55 to move inwardly under the action of the springs 59, 50 60, 61 and 62. In this position the stipple plates are immediately above the end and one side face of each of the mold cavities and, as the rams descend these stipple plates enter the molds and form liners therefor, the 55 displaced material escaping through the vent slots 66. As is customary, the lower battery of rams 11, 12, 13 and 14 ascend as the upper battery 15, 16, 17 and 18 descend compressing the material therebetween and 60 against the side faces and liner plates of the mold. Due compression having been exerted upon the material in the molds both sets of rams move upwardly until the bricks within the mold reach the level of 65 the discharge table 20, this position being

indicated in Fig. 4. Further ascent of the rams 15, 16, 17 and 18 causes the roller 29 to engage the trip 30 quickly swinging the stipple plates 37, 38, 39, 40, 41 and 42 to an elevated position away from the brick face 70 and at the same time moving the stipple plates 54 and 55 away from the brick face. Thereupon the plunger 64 moves forward with a new load of material, the projection 64^a pushing the formed brick off the lower 75 ram onto the discharge table 20 as shown in Fig. 4 and filling the mold for the next set of bricks; the operation being then repeated.

I claim:

1. In a brick machine, the combination with the mold, of stippling plates in operative relation with said mold, means to bring the same into pressure contact with the face of the bricks, and means to remove the same 85 out of such contact.

2. In a brick machine, the combination with the mold, of stippling plates in operative relation with said mold, means to bring the same into pressure contact with the face 90 of the bricks, and means to remove the same out of such contact suddenly in a lateral direction.

3. In a brick machine, the combination with the mold, of stippling plates forming 95 mold liners, means to withdraw the plates with the bricks from the mold, and means to remove the plates in a lateral direction out of contact with the bricks.

4. In a brick machine, the combination 100 of a mold, rams movable toward and from each other to compress the material within the mold, a stippling plate mounted to move toward and from the brick face, means to actuate said plate, and means to 105 force the brick material and plate into pressure contact.

5. In a brick machine, the combination of a mold, a ram to compress the material within the mold, a stippling plate mounted 110 to move with the ram into the mold to form a liner therefor and out of the mold with the formed brick, and means to quickly remove the stippling plate away from the formed brick after leaving the mold.

6. In a brick machine, the combination of a mold, rams relatively movable to compress the material within the mold, a stippling plate hinged to one of the rams and arranged to move therewith into the mold to 120 form a liner therefor, and means actuated by the withdrawing rams to swing the stippling plate away from the formed brick after leaving the mold.

7. In a brick machine, the combination of a mold, rams movable toward and from each other to compress the material within the mold, a pair of stippling plates mounted on one of the rams, one of said plates being hinged to swing to a vertical position and 125

- the other to move in a right line, both of the plates adapted to enter the mold with the rams and to form a liner therefor, and means actuated automatically by the ascending rams to swing the first mentioned stippling plate clear of the formed brick and move the other stippling plate in a right line away from the brick as the latter leaves the mold.
- 10 8. In a brick machine, the combination of a mold, rams movable toward and from each other to compress the material within the mold, a pair of stippling plates, a rock shaft having one of the plates attached thereto to swing toward and from a vertical position above one side of the mold, a wedge member actuated by the rocking of the shaft to move the other stippling plate in a right line toward and from a position above one side of the mold, the two plates adapted to descend with the ram into the mold and to form liner faces therefor and to be removed with the ram from the mold after the forming of the bricks, and means actuated by the ascending ram to remove the stippling plates laterally away from the face of the formed brick.
- 15 9. In a brick machine, the combination with the mold, relatively movable rams for compressing the material within said mold, a rock shaft bodily movable with one of said rams, a stippling plate attached to said shaft to move therewith and to swing to and from a position above one side of the mold, said stippling plate movable with the ram into the mold to form a liner therefor, means arranged to rock the shaft as the ram ascends bringing the plate clear of the mold in order to swing the plate out of contact with the 40 formed brick.
- 20 10. In a brick machine, the combination with a mold, relatively movable rams arranged to compress the material within said mold, a pair of angularly disposed rock shafts intergeared, each of the shafts having hinged thereto a stippling plate arranged to swing as the shaft is rocked to a position above one side of the mold and also to a position removed therefrom, the rock shafts 45 having resilient means to rock the same in one direction and also provided with a tappet arm, and means to engage said tappet arm to rock the shaft in the opposite direction whereby to move the stippling plate into and out of contact with the brick material to surface the face of the formed brick after leaving the mold, the 50 mold being provided with a vent slot for the escape of the material displaced by the entering plate.
- 25 11. In a brick machine, the combination of a plurality of spaced molds arranged in line, rams arranged to compress the material within the mold, a pair of angularly disposed intergeared rock shafts disposed along one side and one end of the series of molds, each of the shafts having hinged thereto a stippling plate arranged to swing as the 55 shaft is rocked to a position above one side of the mold and also to a position removed therefrom, the rock shafts having resilient means to rock the same in one direction and also provided with a tappet arm, and means to engage said tappet arm to rock the shaft in the opposite direction whereby to move the stippling plate into and out of contact with the brick material to surface the face of the formed brick.
- 30 12. In a brick machine, the combination of a plurality of spaced molds arranged in line, rams arranged to compress the material within the mold, a pair of angularly disposed intergeared rock shafts disposed along one side and one end of the series of molds, each of the shafts having hinged thereto a stippling plate arranged to swing as the 35 shaft is rocked to a position above one side of the mold and also to a position removed therefrom, the rock shafts having resilient means to rock the same in one direction and also provided with a tappet arm, and means to engage said tappet arm to rock the shaft in the opposite direction whereby to move the stippling plate into and out of contact with the brick material to surface the face of the formed brick, another stippling plate mounted to move with the rams toward and from the mold and also in a right line at an angle to the movement of the rams, a wedge member arranged to act on the last mentioned stippling plate and to be actuated by the rocking of the shaft.
- 35 13. In a brick machine, the combination of a plurality of spaced molds arranged in line, rams arranged to compress the material within the mold, a pair of angularly disposed intergeared rock shafts disposed along one side and one end of the series of molds, each of the shafts having hinged thereto a stippling plate arranged to swing as the shaft is rocked to a position above one side of the mold and also to a position removed therefrom, the rock shafts having resilient means to rock the same in one direction and also provided with a tappet arm, and means to engage said tappet arm to rock the shaft in the opposite direction whereby to move the stippling plate into and out of contact with the brick material to surface the face of the formed brick, other stippling plates arranged within the interspaces of the rams to move with the rams and also at right angles toward and from the adjacent molds, wedge members arranged to act on the last mentioned plates and to be actuated by the rocking of the shafts, the plates adapted to descend with the rams into the molds and to 40 form liner faces therefor and to withdraw from the molds with the formed brick.
- 40 14. In a brick machine, the combination of a mold, a ram to compress the material within the mold, a stippling plate mounted to move with the ram into the mold to form a liner therefor and out of the mold with the formed brick, and means to quickly remove the stippling plate away from the formed brick after leaving the mold, the 45 mold being provided with a vent slot for the escape of the material displaced by the entering plate.
- 45 15. In a brick machine, the combination of a mold, rams movable toward and from each other to compress the material within the mold, a pair of stippling plates mounted on one of the rams, one of said plates being hinged to swing to a vertical position and the other to move in a right line, both of the plates adapted to enter the mold with the rams and to form a liner therefor, and means actuated automatically by the ascending rams to swing the first mentioned stippling plate clear of the formed brick and 50

move the other stippling plate in a right line away from the brick as the latter leaves the mold, the mold being provided with vent slots in line with the entering plates for the escape of the surplus material displaced by said plates.

In witness whereof I have hereunto signed
